His Attorney.

UNITED STATES PATENT OFFICE

EUGENE D. EBY, OF PITTSFIELD, MASSACHUSETTS, ASSIGNOR TO GENERAL ELECTRIC COMPANY, A CORPORATION OF NEW YORK

FLUID FILLED HIGH TENSION TERMINAL

Application filed April 27, 1932. Serial No. 607,748.

The present invention relates to terminals for high tension electric currents and especially to terminals for use with high tension cables having a channel filled with fluid insulation.

Briefly stated such terminals comprise a metal base portion or member which is sealed to the sheath of the conductor, a relatively tall chambered insulator, commonly made of porcelain, into which the conductor extends, a metal cap for the porcelain, a means extending through the cap by which current is conveyed from or to the conductor, and a fluid filling for the chamber of the insulator and cable.

A terminal to fulfill all of the exacting service requirements should have means to compensate for plus and minus variations in the height of the porcelain insulator; means to compensate for the expansion and contraction of the conductor; means to control the fluid within the cable or conductor during assembly of the parts; means to free the conductor core and terminal parts of foreign matter, a fluid controlling valve and means accessible from a region outside of the terminal to lock the valve in its open position after the parts are assembled and ready for normal operation, which means also permits of subsequently opening the valve should occasion therefor arise.

The object of my invention is the provision of a terminal of improved construction which will fulfill all of the exacting requirements above specified, and which is also of simple and rugged construction.

For a consideration of what I believe to be novel and my invention, attention is directed to the accompanying description and the claims appended thereto.

In the drawing which is illustrative of my invention, Fig. 1 is a view in elevation of a terminal; Fig. 2 is an enlarged sectional view of a part of the terminal; Fig. 3 is a detail illustrating the fluid controlling valve, and Fig. 4 is a sectional view taken in line 4-4 of Fig. 2.

5 indicates a metal base having a flange or other means whereby it may be support-

ed in a vertical position. To the lower end of the base is secured a fluid containing metal sheathed cable 6, as by a wiped soldered joint 7 for example. Supported by the base is a porcelain or equivalent insulator 8 having numerous projections or ribs 9 to increase the creepage surface for electric currents. The insulator is relatively tall, of relatively small diameter and has a central chamber 10 containing fluid insulation, such as thin degasified oil for example. Located within the chamber are one or more cylindrical barriers 10^a. Such insulators are liable to vary considerably in length due to shrinkage in the firing operation. The lower end is seated on the metal base and secured thereto by a fluid tight joint in the usual way. Seated on the top of the insulator is a metal cap comprising a member having a horizontal flange 11 and a depending or inset portion 12 of considerable length having a central opening of hexagonal or other shape, other than round, as shown in Fig. 4, to prevent relative turning of it and the terminal parts extending therethrough. By making the inset 12 of considerable depth, it will permit of considerable variation in the height of the insulator while preserving the desired relation with the conductor parts. Surrounding the upper end of the insulator and secured thereto by cement is a metal ring 13 to which the flange of the cap member is secured by numerous bolts. Between the cap and the top of the insulator is a flat gasket to make a fluid tight connection.

The means for transmitting current from the cable to the outside of the insulator comprise two members, one being supported directly by the conductor and indirectly by the base, the other being supported by the metal cap. Extending through the central opening in the cap member is a stud or terminal member 14, the lower end of which is shaped to prevent it from turning within the opening in the inset as shown in Fig. 4. The upper end of the stud is externally screw threaded and mounted thereon is a nut 15, the latter being seated on a shoulder on the

cap member. Enclosing the upper end of the stud is an internally screw threaded hollow terminal holder 16 having a flange at its lower end resting on the nut 15. The terminal holder is secured in place by a clamping ring 17 and numerous bolts. Between the meeting surfaces is a gasket to ensure a fluid tight joint.

18 indicates the insulation on the strand 10 ed conductor 19, and 20 hand wrapped insulation such as varnished cambric applied after the terminal parts are assembled on the conductor. The conductor is hollow and in the upper end thereof is located a tube 21 for supporting the strands of the conductor and forming a continuation of the conductor core. 22 indicates a lower terminal member or holder having a socket 23 in its lower end to receive the strands of 20 the conductor, there being small holes 24 in the wall of the socket through which string solder is fed to unite the parts. The holder is provided with a valve seat 25 opening into the core of the cable. Above this 25 are one or more lateral ports 26 to permit fluid to flow between the core of the cable and the chamber 10 of the insulator. In addition to being soldered to the tube the holder is also secured thereto by set screws 27. 30 The upper end of the member has a tubular extension 28 acting as a spacer to hold the flexible connectors, to be referred to later, away from the central parts. The member is also screw threaded and mounted in the 35 threaded part is a guide tube 29; the latter extends into the hollow terminal member above and is internally threaded for a short portion of its length to receive the threaded part of the valve 30, and also is provided 40 with lateral ports 33 to permit the passage of fluid.

From the structure thus far described, it will be seen that the cable and its terminal parts are supported by the metal base 5 and 45 that the stud 14 and associated parts are supported by the cap of the insulator. To compensate for unequal expansion and contraction of the various parts as they heat and cool in service, the upper and lower 50 terminal members are electrically united by numerous flexible connectors 34, the latter being made of braided wire having end caps which are pinned and soldered to the terminal parts.

55 In addition to compensating for expansion and contraction in an axial direction, the flexible connectors also permit of a limited misalignment of the upper and lower terminal members which is advantageous as 60 it avoids objectionable strains on any of the parts. In other words, no harm will result if the metal cap is not exactly parallel with the base, as it should be. In this connection, it will be noted that there is considerable lateral clearance between the various tubu-

lar elements located in or forming parts of the upper half of the terminal.

The valve 30 has a long tubular stem 35, the upper end of which is slotted as indicated at 36. In order to rotate the valve both to seat and unseat it, a small rod 37 is provided which has a pin 38 entering the slot. The upper end of the rod is secured to a short screw or plug 39 located at the top of the terminal. The screw, rod 37 and pin 38 serve as a wrench to open and close the valve and form a permanent part of the terminal. During assembly of the terminal, the valve is closed to prevent escape of fluid from the cable and for normal operation is wide open. Prior to assembling the part 16 in place the valve may be removed and a rod or other implement inserted in the tube to ensure that the valve seat and core of the conductor are free of foreign matter. Assuming that the valve is closed and that it is desired to open it, the screw 39, rod 37 and pin 38 are used as a wrench, as indicated in Fig. 3 and the valve is moved upward to the position shown where it is either out of engagement with the screw threads in the tube 29 or at least only one or two threads are engaged. To seat the screw 39 without closing the valve, said screw is moved axially into engagement with the threads in the end of the part 16, the pin and slot or slip connection between the rod and tube 35 permitting of this. As soon as the threads engage, the valve will rotate with the screw 39, but since the valve is separated from its seat by a distance substantially greater than the length of the threaded part of the screw, the effect will be to move the valve downward by an amount determined by the length of the thread on the screw, but not enough to either close the ports 26 or the valve seat or open 100 35 in the lower terminal member. Owing to the pin and slot connection, unequal expansion of the various parts of the terminal cannot cause any binding or injurious action on the valve or its actuator. Once the screw is seated it holds the valve locked against further movement.

The upper end of the part 16 of the upper terminal member is externally threaded to receive the nuts 40 by means of which a conductor means leading to or from an electrical apparatus may be secured.

Due to the hexagonal surfaces on the upper terminal member 14 and to the campanion surfaces or wall defining the bore in the bottom of the inset 12, as shown in Fig. 4, the member 14 is prevented from turning when a wrench is applied to tighten the part 16 thereon. Preventing relative turning of these parts also prevents torsional strains from being transmitted to the flexible connectors which being of rather light material might be injured thereby.

Prior to permitting insulating fluid to flow between the cable core and the interior or chamber 10 of the insulator the parts are carefully evacuated and filled with degassed oil. In this respect the prior practice may be followed and therefore needs no description.

What I claim as new and desire to secure by Letters Patent of the United States, is,—

1. An electric terminal comprising a metal base and cap, a chambered insulator located between the two and sealed at its ends thereby, a hollow conductor entering the insulator and supported by the base, a hollow terminal member carried by the conductor having a screw threaded portion and a port, a hollow terminal member carried by the cap, a flexible current carrying connector between the members, a valve seat on the first member through which and the port fluid flows between the conductor and the chamber, a screw threaded valve engaging the threads on the first mentioned member and cooperating with the seat to control the flow of fluid, a divided actuator for the valve having one part extending through the hollow member carried by the cap to the outside thereof, means permitting relative axial movements of the parts of the actuator and preventing relative rotation of said parts, and a body of fluid insulation filling the chamber and conductor.

2. An electric terminal comprising a metal base and cap, a chambered insulator located between the two and sealed at its ends thereby, a hollow conductor entering the insulator and supported by the base, a hollow terminal member carried by the conductor, a hollow terminal member carried by the cap, a flexible current carrying connector between the members, a valve seat and port in the first member through which fluid flows between the conductor and the chamber, a screw threaded valve, a guide tube having screw threads to receive the valve carried by the terminal member on the conductor and extending into the hollow member an actuator for the valve extending through the guide tube and comprising a rod and longitudinally slotted tube, a pin mounted in the rod and traveling in the slot in the tube, a screw for closing the outer end of the hollow member and to which the rod is secured, and a body of insulation filling the chamber and conductor.

3. In combination, an insulated, fluid filled conductor, tubular means connected to and forming a continuation of the conductor, a valve movable within the means, said means and valve having cooperating screw threads, a seat for the valve in said means, a port in the means controlled by the valve,

a screw plug for closing one end of the means, and an actuator for the valve comprising two principal parts arranged in telescope relation, one of the parts being permanently attached to the valve and the other to the screw plug, and a pin carried by one of the parts and engaging the other to permit of relative longitudinal movement and prevent relative rotary movement.

4. An electric terminal comprising a metal base and cap, a chambered insulator situated between the base and cap and sealed at its ends thereby, a hollow core conductor secured to the base and extending into the chamber of the insulator, a hollow terminal member secured to the conductor and forming a continuation thereof, said member having a valve seat and a port through which communication is established between the said chamber and the core of the conductor, a screw threaded valve located within the member and cooperating with the seat to control the port, a second terminal member carried by the cap and projecting outwardly through it from said chamber, a yielding connection conveying current between the members, an actuator for the valve accessible at the outer end of the second terminal, a slip connection between the valve and actuator permitting relative axial movements and preventing relative rotary movements, and a body of insulation filling the core of the conductor and the chamber of the insulator, said fluid being free to flow from one to the other when the valve is open.

5. An electric terminal comprising a metal base and cap, a chambered insulator situated between the base and the cap and sealed at its ends thereby, a hollow core conductor secured to the base and extending into the chamber of the insulator, a hollow terminal member secured to the conductor and forming a continuation thereof, said member having a valve seat and a lateral port, a guide tube carried by the member and screw threaded for a short distance near its lower end, a valve threaded for engagement with the threads on the tube and cooperating with the seat to control the passage of fluid through the port, a hollow terminal member carried by the cap into which the guide tube extends, a current carrying flexible connection between the members, a divided actuator for the valve having a part extending through the terminal member carried by the cap to the outside thereof, said actuator having a means for closing the outer end of the member and a slip connection between the parts thereof, and a body of fluid filling the conductor and the chamber of the insulator.
